UNITED STATES PATENT OFFICE.

JAMES H. BLAIR, OF QUEBEC, QUEBEC, CANADA.

ROD FOR CLEANING RIFLES AND THE LIKE.

933,285.

Specification of Letters Patent.

Patented Sept. 7, 1909.

Application filed November 21, 1908. Serial No. 463,933.

To all whom it may concern:

Be it known that I, JAMES H. BLAIR, subject of the King of Great Britain, residing in Quebec, in the Province of Quebec and 5 Dominion of Canada, have invented certain new and useful Improvements in Rods for Cleaning Rifles and the Like, of which the following is a specification.

This invention comprehends certain new 10 and useful improvements in devices for use in cleaning the barrels of rifles or other firearms, and the invention has for its object a simple, durable and efficient construction of gun-cleaning rod which is constructed in 15 a plurality of sections that are so connected by a chain as to be adapted to be effectually maintained in operative position and to be knocked down with facility, when not desired for use, to provide a compact structure 20 which is susceptible of being carried in a pocket without inconvenience, the device possessing certain other advantages that will become at once apparent as the invention is hereinafter disclosed, over the ordinary rods 25 of this character in general use.

With this and other objects in view that will more fully appear as the description proceeds, the invention consists in certain constructions and arrangements of the parts 30 that I shall hereinafter fully describe and then point out the novel features thereof in the appended claims.

For a full understanding of the invention and the merits thereof, and to acquire a 35 knowledge of the details of construction, reference is to be had to the following description and accompanying drawing, in which:

Figure 1 is a longitudinal section of a gun-cleaning rod constructed in accordance with 40 my invention; Fig. 2 is a plan view showing the position of the parts when the device is knocked down; Fig. 3 is a detail perspective view of the handle; Fig. 4 is a detail 45 tail sectional view of the forward rod section; Fig. 5 is a top plan view of the end-piece of the chain; Fig. 6 is an enlarged sectional view on the line 6—6 of Fig. 2.

Corresponding and like parts are referred 50 to in the following description and indicated in all the views of the drawing by the same reference characters.

My improved gun-cleaning device consists 55 essentially in a plurality of sections 1 that are designed to be placed end to end to form

a rod of the desired length, and which in the present instance, are cylindrical and hollow, as shown, and are interiorly enlarged at one end to receive the reduced end of the adjacent section, to form a slip joint therewith. 60 In order to hold the various sections associated, a chain or other suitable flexible bond 2 is passed longitudinally therethrough and is adapted to exert a tension between the opposite ends of the rod to prevent any relative 65 longitudinal movement of one of the sections, as would probably result in said section slipping out of engagement with the others. At one extremity, the chain 2 carries an endpiece 3 which fits in the section 1^a 70 at the forward end of the rod, and which is formed in its periphery with an annular groove 4, a plurality of lugs 5 being punched inwardly from the forward section 1^a and being received in the groove to obviously 75 establish a swivel connection between the section 1^a and the end piece 3. At its other or free end, the chain preferably carries a split ring 6, and near such end extends outwardly through a hollow handle 7 that is 80 mounted upon the rear end section 1^b and that is substantially Y-shaped, as shown, and is bifurcated at its extremity to provide oppositely and laterally curved fingerpieces 8. One of these fingerpieces is formed with 85 a claw 9 with which the free or rear end of the chain 2 is designed to be engaged to hold the chain taut, and in order to further regulate the tension between the opposite ends of the rod, the handle 7 is threaded upon the 90 rear end section 1^b, as indicated at 10, and is adapted to be turned in one direction or the other to effect the tightening or loosening of the chain as desired. It is to be particularly 95 observed that inasmuch as the forward end of the chain is connected to the section 1^a, through the instrumentality of a swivel joint, the liability of the chain becoming twisted as the handle is turned, is effectually precluded. At its forward end, this rod carries 100 a head, the body portion 11 of which has a shank 12 that fits loosely within the forward section 1^a and is swiveled therein, in a manner similar to the endpiece 3, that is by having lugs punched from the section 1^a into a 105 groove in its periphery. This body portion is provided intermediate of its ends with a swab-carrying member 13 which, in the present instance, is in the form of a bar that is square in cross section and less in thickness 110

than the diameter of the body portion, so as to provide opposing shoulders 13^a, the swab being wound around the member 13 between the opposing shoulders, as shown, and the bar being preferably serrated or roughened in any suitable manner so as to engage the swab, to assist the shoulders in maintaining the same against accidental displacement as the rod is drawn through the barrel of the gun. At the forward extremity of the body portion, the latter is formed with a threaded stud 14 upon which a brush 15 of any desired or approved construction, is designed to be detachably mounted. Since the head is rotatably connected to the forward end of the rod, it will be noted that it is rendered susceptible of rotating as the rod is pushed through the gun barrel, thereby permitting the brush 15 and the swab to turn with the rifling, in case the cleaner is used with a barrel of this character.

In the practical use of a gun-cleaning rod constructed in accordance with my invention, when it is desired to separate the parts to knock down the device, the handle 7 is turned upon the rear section 1^b in a direction to loosen the chain 2, and the rear end of this chain is then disengaged from the claw 9, thereby relieving the tension between the opposite ends of the rod, and permitting the various sections to be shifted longitudinally to disengage the parts in slip joints. The various sections are then folded over, one upon the other, as clearly illustrated in Fig. 2, and this manifestly produces a compact structure which may be conveniently packed for shipping purposes or readily carried in one's pocket.

From the foregoing description, in connection with the accompanying drawing, it will be apparent that I have provided an improved gun-cleaning rod which is composed of a plurality of sections that may be knocked down or returned to an operative position with facility; which provides means for connecting the parts so as to preclude the possibility of any of the same becoming lost or mislaid while the parts are disassociated; which embodies to a marked degree the characteristics of simplicity, durability and efficiency of construction and operation, and which may be easily and cheaply manufactured so as to be placed upon the market at a price not too great to prevent the general adoption of the device.

Having thus described the invention, what I claim is—

1. A gun-cleaning rod comprising a plurality of hollow sections having a slip joint connection, a hollow handle mounted upon the section at one end of the rod and bifurcated to form oppositely disposed fingerpieces, a chain secured to the section at the other end of the rod and passing longitudinally through all of the sections and the

handle, and means carried by one of the fingerpieces for detachably engaging the chain.

2. A gun-cleaning rod comprising a plurality of hollow sections having a slip joint connection, a hollow handle mounted upon the section at one end of the rod and bifurcated to form oppositely and laterally disposed fingerpieces, one of said finger pieces being formed with a claw, and a chain connected to the section at the other end of the rod and passing longitudinally through all of the sections and the handle and adapted to be engaged with the claw.

3. A gun-cleaning rod comprising a plurality of hollow sections having a slip joint connection, a hollow handle mounted upon the section at one end of the rod and bifurcated to form oppositely and laterally disposed fingerpieces, one of the fingerpieces being formed with a claw, and a chain connected to the section at the other end of the rod and passing longitudinally through said sections and the handle and adapted for engagement with the claw, the handle being threaded upon the first named section, as and for the purpose specified.

4. A gun-cleaning rod comprising a plurality of hollow sections having a slip joint connection, the section at one end of the rod being exteriorly threaded, a hollow handle working upon said threaded section and bifurcated to form oppositely and laterally disposed fingerpieces, one of which is formed with a claw, a chain swiveled to the section at the other end of the rod and passing longitudinally through said sections and the handle and arranged for engagement with the claw.

5. A gun-cleaning rod comprising a plurality of hollow sections having a slip joint connection, the section at one end of the rod being exteriorly threaded, a hollow handle working upon said threaded section and bifurcated to form oppositely and laterally disposed fingerpieces, a chain provided at one extremity with an endpiece fitting in the section at the other end of the rod and formed in its periphery with an annular groove, said last named section having a plurality of lugs punched therefrom and received in the groove to swivel the endpiece in position, the chain extending longitudinally through all of the sections and the handle, and means carried by one of the fingerpieces for detachably engaging the chain.

6. A collapsible gun-cleaning rod comprising a plurality of tubular sections, a claw carried by one of the terminal sections, and a flexible bond secured to the opposite terminal section and passed through all of the tubular sections and adapted at its free end to be detachably engaged with the claw.

7. A collapsible gun-cleaning rod com-

prising a plurality of tubular sections, a hollow handle fitted to one terminal section, a flexible bond secured to the opposite terminal section and passed freely through all 5 of the said sections and the handle, and means carried by the handle for adjustably engaging the bond to maintain the sections in alinement.

8. A collapsible gun-cleaning rod comprising a plurality of tubular sections, a hollow handle mounted on one terminal section, and a flexible bond secured to the opposite terminal section and passed through all 10 of said sections and the handle, the handle being adapted to detachably engage the free 15 end of the bond and being adjustable longitudinally on the corresponding terminal section, whereby to exert linear tension upon the bond to maintain the sections in alinement.

9. A collapsible gun-cleaning rod comprising a plurality of hollow sections, a hollow handle threaded on one terminal section, and a flexible bond secured to the opposite terminal section and passed through all 25 of said sections and the handle, the handle being adapted to engage the bond and being designed to be adjusted on the corresponding terminal section to exert linear tension 30 on the bond.

10. A collapsible gun-cleaning rod comprising a plurality of tubular sections, a hollow handle threaded upon one terminal section, and a flexible bond swiveled to the 35 opposite terminal section and passed through all of said sections and the handle, the handle being adapted to engage the free end of the bond and being designed to be turned relative to the corresponding terminal section to 40 exert linear tension on the bond.

11. A collapsible gun-cleaning rod comprising a plurality of tubular sections, a

flexible bond passed through all of said sections and connected to one terminal section, and means disposed at the opposite terminal 45 section for engaging the bond, said engaging means having a rotary longitudinal adjustment to exert linear tension on the bond, the bond being swiveled to the first named terminal section to prevent twisting.

12. A collapsible gun-cleaning rod comprising a plurality of tubular sections, a hollow handle fitted on one terminal section and formed with an outstanding finger-piece, and a flexible bond secured to the 55 opposite terminal section and passed through all of said sections and the handle, the free end of the bond being adapted to be engaged with the finger-piece to hold the sections in alinement.

13. A collapsible gun-cleaning rod comprising a plurality of hollow sections, a flexible bond passing through said sections and provided with an end piece fitted in one 60 end section and formed in its periphery with 65 an annular groove, the said section having a lug punched therefrom and received in the groove to swivel the end piece in position, and means disposed at the opposite end sections for engaging the bond.

14. A collapsible gun-cleaning rod comprising a plurality of hollow sections, a flexible bond passing through said sections and connected to one end section, and a handle mounted upon the opposite end section and having a finger-piece formed with 75 a claw adapted to engage the bond.

In testimony whereof I affix my signature in presence of two witnesses.
